DESIGN FOR A COIN OR TOKEN CON-
TROLLED AMUSEMENT DEVICE

Edward C. Russell, Seattle, Wash.

Application July 3, 1933. Serial No. 48,627

Term of patent 14 years

To all whom it may concern:

Be it known that I, EDWARD C. RUSSELL, a citizen of the United States, residing at Seattle, in the county of King and State of Washington, have invented a new, original, and ornamental Design for a Coin or Token Controlled Amusement Device, of which the following is a specification, reference being had to the accompanying drawing forming a part thereof.

Fig. 1 is a plan view of a coin or token controlled amusement device embodying my new design;

Fig. 2 is a front elevation thereof;

Fig. 3 is a rear elevation thereof; and

Fig. 4 is a side elevation thereof.

I claim:

The ornamental design for a coin or token controlled amusement device as shown.

In witness whereof, I hereunto subscribe my name this 1st day of July, 1933, at Chicago, Illinois.

EDWARD C. RUSSELL.
